Atty's.

UNITED STATES PATENT OFFICE.

ERNEST W. DAVIS, OF OAK PARK, ILLINOIS, ASSIGNOR TO THE BASSICK MANUFACTURING COMPANY, OF CHICAGO, ILLINOIS, A CORPORATION OF DELAWARE.

LUBRICANT COMPRESSOR.

Application filed April 27, 1923. Serial No. 634,970.

My invention relates to improvements in lubricant compressors, and is particularly concerned with the provision of a novel type compressor for supplying lubricant under high pressure to bearings.

The objects of my invention are:

First: To provide a compressor by means of which comparatively large quantities of lubricant can be easily and quickly forced 10 into bearings under high pressure;

Second: To provide a lubricant compressor comprising a container or low pressure cylinder for holding a comparatively large quantity of lubricant, and a high pressure cylinder 15 communicating with said low pressure cylinder and receiving lubricant therefrom.

Third: To provide a lubricant compressor such as described comprising means coacting with the high pressure cylinder which 20 will positively insure the complete discharge from the high pressure cylinder of each successive charge delivered thereto by the low pressure cylinder;

Fourth: To provide a compressor such as 25 described which is particularly adapted to handle grease and the more viscous varieties of lubricant which ordinarily contain more or less air entrapped therein;

Fifth: To provide a compressor such as 30 described in which the suction developed in the high pressure cylinder is used for insuring the delivery of lubricant from the low pressure cylinder to the high pressure cylinder; and

Sixth: To provide a compressor such as 35 described which is simple in construction, rugged and economical to manufacture.

Other objects of my invention will appear 40 as this description progresses, reference being had to the accompanying drawings, in which

Figure 1 is a central longitudinal section through one embodiment of my invention, which is here illustrated as being used for supplying lubricant under pressure to the 45 bearing shown in cross section; and

Figure 2 is a transverse section taken on line 2—2 of Figure 1.

Referring to the drawings, my improved 50 compressor comprises a low pressure cylinder 5, the outer end of which is flared outwardly as shown at 6 and reinforced by a suitable ring 7, the lower side of which is provided with a pedestal or foot 8 for supporting the outer end of the cylinder. The inner end of 55 the cylinder is provided with a closure 9

which has a transversely extending bore formed therein, the inner end 10 of said bore being larger in diameter than the outer end 11, thereby forming a shoulder 12 which acts as a valve seat for the disc-shaped check 60 valve 13 which is yieldingly held in its closed position by means of a suitable compression spring 14 located in the enlarged portion 10 of the bore which is closed by a suitable threaded plug 15. The closure 9 is provided 65 with an opening 16 for establishing communication between the low pressure cylinder 5 and the smaller portion 11 of the transverse bore which forms a high pressure cylinder.

The closure 9 is provided with two concentric annular ribs 17 and 18, to the first of which is secured the inner end of the low pressure cylinder 5. The second annular rib 18 acts as a support for a screen 20 which prevents the passage of dirt through the 70 opening 16 into the high pressure cylinder. An internally threaded boss 21 extends outwardly from the closure 9 in the same direction as the ribs 17 and 18 and is adapted 75 to receive the inner threaded end of the guide rod 22, the inner end of which is provided with a collar 23, the function of which will later be referred to. The outer end of the guide rod 22 is provided with a transversely 80 extending handle 24, by means of which it can be rotated. A follower 25, which can be made of wood or any other suitable material, is slidably mounted upon the guide rod 22, and its diameter is preferably such that its 85 periphery will be spaced slightly from the inner wall of the cylinder 5.

A plunger 26 is slidably mounted in the high pressure cylinder formed by the bore 11. For reciprocating this plunger I provide the closure 9 with an outwardly extending bracket 27 upon which is pivotally mounted a link 28, the upper end of which is bifurcated and carries the pivot pin 29, upon which is pivotally mounted one end of the lever 30. The outer end of the plunger 100 26 is provided with a cap 31 having two bifurcations 32, only one of which is shown, which extend upwardly on opposite sides of the lever 30 and are secured thereto by means of a pivot pin 33 which is located intermediate 105 the ends of the lever 30. The free end of the lever is provided with a handle 34 and the other end of the lever is provided with a projection or stop 35 which is adapted to contact with the face 28' of the link 28 so as to limit 110

the upper movement of the handle 34 relatively to the low pressure cylinder 5. In this manner the handle 34 may be used for carrying the compressor about.

- 5 The closure 9 is provided with a pair of spaced feet 27, only one of which is shown, for supporting the end of the cylinder 5 to which the closure 9 is attached.

10 The upper end of the valve 13 is reduced in area to provide a clearance space for the passage of lubricant and to prevent dirt or other foreign matter from interfering with the proper seating of the valve. The valve is also flattened on a plurality of its sides, as shown at 36, to provide passageways for the lubricant to flow past the valve.

15

The valve chamber formed by the enlarged portion 10 of the bore is provided with a discharge nipple 37 which ends in one element 38 of a swivel connector. The other element 39 of this connector has secured thereto a flexible conduit 40 which ends in a coupling member 41 constructed in a well-known manner for making a sealed connection with a fitting or nipple 42, also of well-known construction, secured to a bearing 43.

In operating my improved compressor the rod 22 is unscrewed from the boss 21 and withdrawn from the low pressure cylinder. The collar 23 on the inner end of the rod causes the follower 25 to be withdrawn with the rod. The low pressure cylinder is then filled with lubricant and the rod and follower are inserted into the open end of the low pressure cylinder. This operation is facilitated by the outwardly flaring portion 6 of the outer end of the low pressure cylinder. The rod is forced inwardly and engaged with the boss 21 leaving the follower 25 in the outer end of the cylinder. After the coupling member 41 has been connected with the fitting 42 which is to receive lubricant, the operator grasps the handle 34 and moves it upwardly, thereby creating a vacuum in the portion of the bore below the plunger 26. When the lower end of the plunger uncovers the opening 16, atmospheric pressure causes the follower 25 to move inwardly and fill the portion of the bore 11 below the plunger 26 with lubricant. The operator thereupon depresses the handle 34, moving the plunger 26 downwardly. The length of the plunger 26 is such that when it is in its extreme inner position, its inner end can contact with and open the valve 13. It will, of course, be seen that if there is lubricant between the inner end of the plunger and the valve 13, downward movement of the plunger 26 will cause this lubricant to be displaced from the smaller portion 11 of the bore into the larger portion, the valve 13 being opened by the flow of lubricant. After the valve 13 has opened slightly and a portion of the lubricant has been displaced from the high pressure cylinder into the portion 10 of the bore, the pres-

sures on the opposite sides of the valve, due to the pressure on the lubricant, will be equalized, thereby leaving the pressure of the spring 14 free to hold the valve 13 against the inner end of the plunger 26 as soon as it projects into the portion 10 of the bore, so that when the plunger is moved upwardly the valve 13 follows it until the valve rests against its seat, thereby preventing any return flow past the valve back to the portion 11 of the bore. In this manner I have provided means which insures the complete displacement of each charge from the high pressure cylinder, so that when the plunger 26 is moved outwardly, it will create a perfect vacuum between its inner end and the valve 13. The provision of means for insuring the complete displacement of the contents of the high pressure cylinder is very important where grease or other heavy lubricants which usually contain entrapped air are to be forced into bearings, because, in the absence of such means, there is a tendency for the air, when it reaches the cylinder of the pump, merely to be compressed and then re-expand in the cylinder without being discharged therefrom, so that the function of the cylinder is destroyed. With my means, however, each charge delivered to the high pressure cylinder, whether it be lubricant, air or a mixture of the two, is completely displaced therefrom so that the return stroke of the plunger creates a complete vacuum in the high pressure cylinder and thereby makes it possible for atmospheric pressure to move the follower 25 inwardly and assure the delivery of successive charges to the high pressure cylinder.

While I have described the details of construction of the preferred embodiment of my invention, it is to be clearly understood that my invention is not limited to these details, but is capable of other adaptations and modifications coming within the scope of the appended claims. 105

Having thus described my invention, what I claim as new, and desire to secure by Letters Patent of the United States, is:

1. A lubricant compressor comprising a low pressure cylinder having a closure for one end thereof, said closure having a bore extending therethrough, the inner end of said bore being larger than the outer end thereof to form a valve seat between the two portions of said bore, said closure having an opening 115 for establishing communication between said cylinder and the smaller portion of said bore, a plunger slidable in the smaller portion of said bore, a valve slidable in the larger portion of said bore, a spring for yieldingly holding said valve on said seat, said plunger being 120 of such length that it can contact with and open said valve, a base for said cylinder extending substantially parallel therewith, and a handle for actuating said plunger extending over said base. 125 130

2. A lubricant compressor comprising a low pressure cylinder having a closure for one end thereof, said closure having a bore extending therethrough, the inner end of said bore being larger than the outer end thereof to form a valve seat between the two portions of said bore, said closure having an opening for establishing communication between said cylinder and the smaller portion of said bore, 10 a plunger slidable in the smaller portion of said bore, a valve slidable in the larger portion of said bore, a spring for yieldingly holding said valve on said seat, said plunger being of such length that it can contact with said 15 valve, and a handle for actuating said plunger.

3. A lubricant compressor comprising a low pressure cylinder having a closure for one end thereof, said closure having a bore extending therethrough, the inner end of said bore being larger than the outer end thereof, a shoulder formed at the junction of the two portions of said bore, a valve slidable in the larger portion of said bore, a spring for yieldingly holding said valve against said shoulder, said closure having an opening for establishing communication between said cylinder and the smaller portion of said bore, a plunger slidable in the smaller portion of said bore, adapted to open said valve near the end of its working stroke.

4. A lubricant compressor comprising a low pressure cylinder having a follower therein, one face of which is exposed to atmospheric pressure, a high pressure cylinder communicating with said low pressure cylinder, a plunger for said high pressure cylinder, said plunger being of such length as to extend outwardly beyond the discharge end of said high pressure cylinder when it is forced inwardly to the end of its stroke, a valve seating against the discharge end of said high pressure cylinder, and a spring for yieldingly holding said valve against its seat.

5. A lubricant compressor comprising a low pressure cylinder, a high pressure cylinder communicating with said low pressure cylinder, a plunger for said high pressure cylinder, said plunger being of such length as to extend outwardly beyond the discharge end of said high pressure cylinder when it is forced inwardly to the end of its stroke, a valve seating against the discharge end of said high pressure cylinder, and a spring for yieldingly holding said valve against its seat, both sides of said valve being subjected to the pressure of the lubricant.

6. A lubricant compressor comprising a low pressure cylinder having a follower therein, one face of which is exposed to atmospheric pressure, a high pressure cylinder communicating with the other end of said low pressure cylinder, a plunger for said high pressure cylinder, and adapted to extend outwardly beyond the end of said high

pressure cylinder, a valve seating against the discharge end of said high pressure cylinder, and a spring for yieldingly holding said valve against its seat, said valve co-acting with said plunger to produce substantially complete displacement of the contents of said cylinder upon each stroke of said plunger.

7. A lubricant compressor comprising a low pressure cylinder open to atmosphere, a high pressure cylinder communicating with said low pressure cylinder, a plunger for completely displacing the contents of said high pressure cylinder, a check valve forming the wall of the discharge end of said high pressure cylinder, said valve being adapted to be opened by contact with said plunger to produce substantially complete displacement of the contents of said cylinder upon each stroke of said plunger.

8. A lubricant compressor comprising a horizontally disposed low pressure cylinder, a vertically disposed high pressure cylinder communicating with said low pressure cylinder, a plunger slidable in said high pressure cylinder, a lever for actuating said plunger, said lever extending over said low pressure cylinder, and means including part of said lever for limiting the upward movement of said lever relatively to said low pressure cylinder, whereby said lever may be used for actuating said plunger and for carrying said compressor.

9. A lubricant compressor comprising a horizontally disposed low pressure cylinder, a high pressure cylinder communicating with said low pressure cylinder, a plunger slidable in said high pressure cylinder, and a lever for actuating said plunger and means including an extension of said lever for limiting the upward movement of said lever relatively to said low pressure cylinder, whereby said lever may be used for actuating said plunger and for carrying said compressor.

10. A lubricant compressor comprising a horizontally disposed low pressure cylinder, one end of which is provided with a closure having a vertical high pressure cylinder formed therein, a plunger in said high pressure cylinder, a base plate at each end of said compressor and a handle extending over said base plates and substantially co-extensive with said low pressure cylinder for actuating said plunger, whereby said low pressure cylinder serves as a lever arm for resisting the force of said handle.

11. A lubricant compressor comprising a relatively long low pressure cylinder, one end of which is provided with a closure having a high pressure cylinder transversely disposed with respect to said low pressure cylinder, an unbiased plunger in said high pressure cylinder, a handle connected to said closure by a link mechanism and having a part of maximum depth pivotally connected to said plunger, said handle extending along said

low pressure cylinder, the latter and said handle forming cooperative levers for reciprocating said plunger in said high pressure cylinder, and a projection on said handle for limiting movement of said handle away from said low pressure cylinder.

12. A high pressure lubricant compressor of the class described comprising a relatively long low pressure cylinder; one end of which 10 is provided with a closure having a high pressure cylinder transversely disposed with respect to said low pressure cylinder, a plunger

reciprocable in said high pressure cylinder, a handle operatively connected to said plunger and extending in the general direction of 15 said low pressure cylinder, said handle and low pressure cylinder constituting cooperative lever means for operating said plunger, and a projection on said handle for limiting movement of said handle away from said low 20 pressure cylinder.

In witness whereof, I hereunto subscribe my name this 23rd day of April, 1923.

ERNEST W. DAVIS.
